Attorney.

UNITED STATES PATENT OFFICE.

CLARENCE HANCOCK, OF LETCHWORTH, ENGLAND.

HEATING APPARATUS.

Application filed January 15, 1924. Serial No. 686,354.

To all whom it may concern:

Be it known that I, CLARENCE HANCOCK, a subject of the King of Great Britain, residing at Letchworth, in the county of 5 Hertfordshire, England, have invented certain new and useful Improvements in Heating Apparatus, of which the following is a specification.

This invention relates to improved means 10 for heating garden propagating frames, foster mothers and the like, which have compartments requiring to be kept at different temperatures.

It is important in apparatus of this kind 15 to provide an evenly distributed gentle heat of the degree required so that the seedlings, in the case of a propagating frame, or the newly hatched chickens, in the case of a foster mother, may enjoy as nearly as possible 20 the proper natural temperature conditions.

One of the objects of the present invention is to provide in a single propagating frame or foster mother having two or more 25 compartments side by side, a self contained heating unit formed of a number of elements of different heat radiating capacity, one of which at least is in the form of a flat tank, so that a gentle heat may be provided uniformly over the whole area of one 30 compartment. The heating unit can be slid endwise as a whole, into the frame or the like so that the several elements lie, respectively, in the compartments which they are 35 required to heat. With this arrangement two or more chambers can be constantly kept at different temperatures, so that, where the invention is embodied in a propagation frame, seedlings which have just begun 40 to shoot may be moved from the warmest chamber into an adjoining chamber having a lower temperature; or where the invention is embodied in a foster mother, one chamber may be kept warm enough for the 45 day old chicks while an adjoining chamber is warmed sufficiently to care for the chicks after they are a few days old, or at any rate during the day time.

A further object is to provide a heating 50 unit of the character mentioned which can be heated from the exterior of the frame or the like by any suitable source of heat, for example a lamp.

The invention is illustrated in the accompanying drawings in which,

Figures 1 and 2 are, respectively, a sectional plan and a front elevation of the invention applied to a propagating frame, and

Figures 3 and 4 are, respectively, a part 60 sectional plan and a front elevation showing the invention applied to a foster mother.

Referring to Figures 1 and 2 of the drawing, 1 is the body of the propagating frame having ends 2 and 3 and partitions 4 and 5 which divide the frame into three compartments, 6, 7 and 8 of substantially equal dimensions. Preferably each compartment is covered separately by a hinged glazed roof 9. The heating unit comprises three 70 flat rectangular tanks 10, 11 and 12, arranged end to end and having their interiors communicating with one another, the unit 10 at one end being largest, the next unit 11 of smaller size and the third 75 unit 12 of still smaller size. In the construction illustrated the heating unit is inserted lengthwise of the frame, openings being formed in the end 2 and in the partition 4 large enough for the passage therethrough of the largest element 10 and the partition 5 having an opening large enough to receive the end of element 11.

The heating unit lies upon or close to the bottom of the frame and, when in position, 85 the largest element 10 thereof covers practically the whole of the floor of compartment 6, the second element 11 covers a part of the floor of the compartment 7 and the third element 12 a still smaller part of the 90 floor of compartment 8.

From element 10 a small extension 14 projects outside the frame under which is placed a suitable heating means, for example, an oil lamp. The extension 14 has in its upper side a plug hole 15 through which the heating unit can be filled with water. When the lamp is lighted and placed in position under the extension 14 all of the water in the heating element is warmed and the units 10, 11 and 12 heat their respective compartments 6, 7 and 8 approximately in proportion to the area of their radiating surfaces. A vent 16 (Fig. 1) may be provided at the end of the smallest unit; and said unit may also have a drain plug 33 through which the heating unit may be emptied when desired.

Instead of an oil lamp a gas burner or other source of heat may be employed. 30 110

and 31 are trays provided in each of the compartments, the lower one of which may, for example, have a bottom of wire mesh upon which damp moss or other suitable material is placed. The upper tray 31 carries the seedlings or the like. In the case of compartments 6 and 7 the trays rest upon the heating element, but in compartment 8 supporting members 32 (Fig. 1) are provided.

Where the invention is applied to a foster mother, as shown, for example in Figures 3 and 4, the heating unit consists of two elements 17 and 18, the larger element 17 as in the case of the propagating frame just described, being in the form of a large flat rectangular tank. This element covers substantially the whole area of the first compartment 19 of the foster mother, but in this case it is arranged in the upper part of the compartment so as to throw the heat downward. The other element 18 of the heating unit may be in the form of a pipe or cylinder which extends through the partition 21 between the two compartments 19 and 20, the difference of temperature in the two compartments being in this case very much more marked than in the case of the garden propagating frame. The water, as in the case of the propagating frame, is heated by means of a lamp or other source of heat placed beneath an extension 22 of the first heating element 17.

For the purpose of removing the heating unit the partition 21 is preferably formed in two parts, the upper half above the pipe 18 being readily removable by sliding it upward from between parallel vertical slides 23. 24 is the usual drawer for affording ready access to the very young chicks or the like within compartment 19, and 25 is a window permitting observation of the interior of compartment 20. Doors 26, 27 are formed in the side of drawer 24 and partition 21, respectively, to permit the transfer of the chicks from compartment 19 to compartment 20.

Instead of the heat being distributed in the several compartments by water in the tanks, the desired effect can be obtained by heating the air in the heating unit, the con-

struction of the latter remaining substantially the same as when water is used.

I claim:

1. Means for heating structures having a plurality of compartments side by side which are required to be kept at different temperatures, comprising a heating unit adapted to be inserted in and removed from the structure and composed of a plurality of integrally-formed communicating heating elements disposed in longitudinal relation and of different dimensions to present different heat radiating areas, each of said elements adapted, when the unit is inserted in the structure, to lie within and to heat a different compartment of the structure.

2. Means for heating structures having a plurality of compartments side by side which are required to be kept at different temperatures, comprising a heating unit adapted to be inserted in and removed from one extremity of the structure longitudinally of the latter and composed of a plurality of water-containing communicating heating elements arranged in endwise relation, one of the end elements being in the form of a flat tank, said elements each presenting a different heat radiating area and each adapted to lie within and to heat a different compartment of the structure.

3. Means for heating structures having a plurality of compartments side by side which are required to be kept at different temperatures, comprising a heating unit insertable in one extremity of the structure to extend longitudinally of the latter, said heating unit being composed of a plurality of communicating heating elements one of which is in the form of a flat tank, said elements successively decreasing in dimensions to present different heat radiating areas and each adapted to lie within and to heat a different compartment of the structure, the element of greatest heat radiating area having an extension adapted to extend outside the structure and to be heated by a source of heat external to the structure.

In testimony whereof I have hereunto set my hand.

CLARENCE HANCOCK.
